UNITED STATES PATENT OFFICE.

ALBERT W. SMITH, OF WASHINGTON, DISTRICT OF COLUMBIA.

ELECTRIC STARTER FOR AUTOMOBILE-ENGINES.

1,144,438.

Specification of Letters Patent.

Patented June 29, 1915.

Application filed June 26, 1914. Serial No. 847,531.

To all whom it may concern:

Be it known that I, ALBERT W. SMITH, a citizen of the United States, residing at Washington, in the District of Columbia, have invented certain new and useful Improvements in Electric Starters for Automobile-Engines, and the following is a specification thereof.

My invention relates to an electric starting system for automobile engines, and its object is to produce a cheap, simple and direct acting starter.

Present systems are costly because of the expensive motor construction used, comprising a laminated core, a special field magnet and coils, and a special large commutator, to obtain low brush contact resistance; also because of the complicated gearing employed, consisting either of a sliding pinion 10 engaging with a ring gear on the fly wheel, or of a gear or chain drive acting through an overrunning clutch, etc.

To avoid the use of a sliding pinion, or a clutch mechanism, or both, I employ a motor that is movable to and from the engine fly wheel, and has a rolling driver acting directly on the fly wheel. The rolling driver is preferably made of hardened steel, and has nurling teeth formed thereon, and the fly wheel has depressions knurled thereon corresponding to and meshing with the teeth of the driver. The motor also has auxiliary magnet poles conforming to the fly wheel, which act when the motor is energized, to 25 pull it toward the fly wheel, and the driver into contact therewith; when the motor is not energized, a spring acts to retain it away from the fly wheel, and the driver out of contact therewith.

To obtain a cheap and simple starting motor, I employ an unlaminated ring core, wound with square copper wire, bared to form a commutating or brush contact surface for the armature. Instead of the usual 30 field magnet, I employ a pole frame without field coils, having poles conforming to the armature, and also poles conforming to the fly wheel. When a current is sent through the armature, by means of brushes having a lead in the direction of rotation, field poles are formed in the pole frame by the armature, which then develops a torque exactly as in the ordinary motor. As the starter is used for only a second or two at a time, there 35 is no appreciable heating, and the slight loss entailed by the use of a solid core is com-

pensated by the absence of stray field or magnetic leakage between pole tips, which occurs when a wound field magnet is used.

With the new driving gear employed by me a high gear ratio, and consequently a high motor speed, can be used. The use of the armature surface for commutation enables the employment of very large brushes with light pressure, and insures a low brush friction and contact resistance, which is of great importance in a low voltage 40 starter.

The drawings show an end view in Figure 1, a side view in Fig. 2, sectional views 45 in Figs. 3 and 4, a modification in Fig. 5 and detail views in Figs. 6 and 7.

1 is the fly wheel mounted on the crank shaft 2, which is journaled in the crank case 3.

The pole frame of the starter consists of the armature poles 4 and 5, the fly wheel poles 6 and 7, and the connecting bridge 8. The armature of the starter consists of the bare faced winding 9 and the unlaminated 50 ring core 10, and is mounted on the armature shaft 11 by means of the spider 12. The rolling driver of the starter consists of the toothed roll 13 formed integrally with the armature shaft 11, which is journaled in 55 the bearings 14 and 15. The starter is movably related to the engine fly wheel 1 by hinging it to the crank case 3 by means of the pin 16.

The pole frame is a steel casting forming 60 the bearing support for the armature, and the hugging magnet for the starter, acting to force the driver 13 against the fly wheel 1. The bore 17 is machined to receive the bearings 14 and 15, which are secured there- 65 in as shown in Fig. 3. The pole pieces 4 and 5 are bored to receive the armature, and the pole pieces 6 and 7 are machined to conform to the fly wheel 1. When the starter is 70 energized the bridge 8 first becomes saturated, after which the magnetic flux is forced through the fly wheel 1, the thickness of the bridge 8 thus determines the flux 75 through the fly wheel, and the pressure exerted on the driver 13.

The construction of the armature is shown 80 in Figs. 3 and 4. The winding 9 is formed of square wire tightly coiled onto the core 85 10, and its ends soldered together. The spider 12 is then inserted as shown in Fig. 90 3; the winding is then soaked with insulating 95 compound and baked, after which its 100

105

110

entire outer surface is bared of insulation and is ground true and smooth to form the commutating face of the armature. The use of square wire enables a perfectly continuous and smooth commutating face to be formed on the armature. Current is supplied to the armature by the brushes 18 and 19, supported by the insulated brush holders 20 and 21, which are secured to the pole pieces 4 and 5.

The circuit terminals are bolted to the brush holders at 22 and 23. The large commutating face of the armature enables the use of large carbon brushes with a light bearing pressure on the armature; thus obtaining the low brush contact resistance required by the low voltage current supply of the starter.

The direction of rotation is determined by a forward lead of the brushes, and is indicated by the arrow in Fig. 1. As the starter is magnetized solely by the armature current, its poles tend strongly to form in line with the brushes and to cause sparking. To prevent 25 sparking I employ the unlaminated core 10, in which eddy currents are generated which cause a lag in the magnetism of the core, and thus act to shift the poles from the brush diameter forward to a position under the pole pieces 4 and 5. Sparking is also minimized by the fact that only a single turn of the winding is commutated at a time. The use of a solid core is not objectionable in a starter, as due to its intermittent use only slight heating is caused by the eddy currents in the core, and the energy loss due thereto is negligible. As the magnetic field of the starter is developed in and by the armature itself, magnetic leakage cannot occur; and, if worked below saturation, its torque will be directly proportional to the current, thus giving the starter the true series motor characteristics required for engine starting.

The driver 13 and shaft 11, a detail view of which is shown in Fig. 6, are formed of a single piece of tool steel and hardened. The driver 13 has helical teeth of V-shape milled thereon, as shown in Figs. 3 and 6 at 50 24. The teeth 24 engage with corresponding depressions 25 on the fly wheel 1. The depressions 25 are formed by means of a nurling tool and are made only deep enough to enable the teeth 24 to exert a positive driving action on the fly wheel 1. The use of the depressions 25 also has the advantage over a smooth wheel surface that less pressure is required on the driver 13; but their use is not essential to the operation of the 55 driver, which will operate on the smooth surface of the fly wheel, and can be so employed when the starter is applied to an engine already in use. When the starter is applied to an engine with a smooth fly wheel, the driver teeth 24 are made quite

sharp, and the thickness of the bridge 8 is reduced to a minimum, so that most of the flux will be shunted through the fly wheel, thus increasing the pressure on the driver 13 and enabling it to form a nurling 25 on the fly wheel. After a period of use the teeth 24 lose their keenness and their nurling action then ceases. The object in using helical teeth 24 is to obtain a uniform and smooth driving action of the teeth, and also to produce an end thrust in the shaft 11 to oppose the end pull between the armature and pole frame. The driver 13 can also be used with a smooth face, as shown in Fig. 5, but the pressure on the driver must then be greatly increased.

The driver 13 projects slightly beyond the face of the poles 6 and 7, so that when the driver is in contact with the fly wheel the poles will clear the same by a small amount. When the starter is idle the driver 13 is held just clear of the fly wheel by means of the spring 26 acting to engage the notch 27 with the retaining pin 28, as shown in Figs. 2 and 7.

The starter can be applied to either side or to the top of the fly wheel, as desired or most convenient. In Figs. 1 and 2 the starter is shown as applied to the fly wheel on the valve side of the engine. This is a good location for the starter when the fly wheel is exposed. When, however, the fly wheel is inclosed by a casing 29, as shown in Fig. 5, I prefer to apply the starter to the top of the fly wheel as shown. The starter is then hinged to the casing 29 at 30, and is supported at its free end by the compression spring 26.

When it is desired to start the engine, a current is sent through the starter from a battery, thus developing in the core 10 a magnetic flux which completes its circuit through the bridge 8 and the fly wheel 1. The starter then produces a driving torque, and at the same time forces the driver 13 against the fly wheel 1 by means of magnetic attraction between it and the poles 6 and 7. The engine is then driven by the starter at the required starting speed until started, when the battery current is cut off and the starter resumes its idle position by the action of the spring 26.

Having explained my invention in detail, I will now point out some of its advantages.

Great simplicity, cheapness of construction, and directness of operation are made possible by the employment of the self commutating and self magnetizing armature and the self engaging driver for the starter. The use of the armature face for commutation saves the cost of a special commutator and enables the use of large carbon brushes with a low contact resistance, thus removing all objections to a six volt current supply for the starter. The use of the armature

current for magnetizing the starter precludes magnetic leakage and faulty operation due thereto. The use of rolling gearing requires no overrunning clutch devices, and 5 provides a direct, positive and reliable drive with a high gear ratio of from twenty or thirty to one for the starter.

Another valuable feature of the starter is its great compactness, and the fact that it 10 can be applied directly to the fly wheel without in any way interfering with or crowding the other equipment of the engine.

While the starter is especially adapted for automobile use, it can also be applied to 15 stationary engines and to any other types of machinery requiring auxiliary starting.

Having now fully described my invention, I desire to state that the same is not limited to the exact construction and relation of elements shown, as these can be modified and combined in other ways without departing 20 from the essential features of the invention.

What I claim as my invention is:

1. The combination with a fly wheel of a 25 non-self-starting engine, of an electric starting motor, movably mounted with relation to said fly wheel, and having a rolling driver in operative relation therewith; a spring acting to retain said motor, when unenergized, away from said fly wheel, and said driver out of contact therewith; and auxiliary pole pieces for said motor, forming a part of the magnetic field circuit thereof, said pole pieces conforming to said fly 30 wheel, and acting to pull said motor toward said fly wheel, and to force said driver into contact therewith, when the motor is energized for starting the engine.

2. The combination with the fly wheel of a 40 non-self-starting engine, of an electric starting motor, movably mounted with relation to said fly wheel, and having a rolling driver of hardened steel in operative relation therewith, said driver having nurling teeth or 45 projections formed thereon; a spring acting to retain said motor, when unenergized, away from said fly wheel, and said driver out of contact therewith; and auxiliary pole pieces for said motor, forming a part 50 of the magnetic field circuit thereof, said pole pieces conforming to said fly wheel, and acting to pull said motor toward said fly wheel, and to force said driver into con-

tact therewith, when the motor is energized for starting the engine. 55

3. The combination with the fly wheel of a non-self-starting engine, of an electric starting motor, movably mounted with relation to said fly wheel, and having a rolling driver of hardened steel in operative relation therewith, said driver having nurling teeth or 60 projections formed thereon, and said fly wheel having depressions corresponding with the nurling teeth of said driver, formed thereon; a spring acting to retain said motor, when unenergized, away from said fly wheel, and said driver out of contact therewith; and auxiliary pole pieces for said motor, forming a part of the magnetic field circuit thereof, said pole pieces conforming 65 to said fly wheel, and acting to pull said motor toward said fly wheel, and to force said driver into contact therewith, when the motor is energized for starting the engine.

4. In an electric starting motor for non-self-starting engines, in combination, a pole frame without field windings, having armature poles, and also poles conforming to the fly wheel of the engine; a self magnetizing ring armature mounted on a shaft 80 journaled in said pole frame, a driving element on said shaft in operative relation with said fly wheel; a self commutating winding for said armature, formed of square wire with a bared contact or brush 85 surface, and contact brushes having a lead in the direction of rotation, and bearing directly on said winding.

5. In an electric starting motor for non-self-starting engines, in combination, a pole 90 frame without field windings, having armature poles, and also poles conforming to the fly wheel of the engine; a self magnetizing ring armature with an unlaminated core, mounted on a shaft journaled in said 95 pole frame, a driving element on said shaft in operative relation with said fly wheel; a self commutating winding for said armature, formed of square wire with a bared contact or brush surface, and contact brushes 100 having a lead in the direction of rotation, and bearing directly on said winding.
